BOILER SYSTEM

Vincent V. Veenschoten, Erie, Pa., assignor to
 Northern Equipment Company, Erie, Pa., a corporation of Pennsylvania

Application August 4, 1936, Serial No. 94,294

11 Claims. (Cl. 122—451.1)

This invention relates to systems for regulating the flow of feed water to boilers. It has for one of its objects providing for manual control of the flow if any occasion should arise. An ordinary feed water regulator is arranged to operate in the normal manner controlling the opening of the feed water valve; but if the operator wishes to raise or lower the water level in the boiler independently of the regulator he can do so by manual operation. A further object is to provide means whereby this additional control occurs automatically when necessary to the safe or efficient operation of the boiler system. A further object is to automatically signal to the operator when abnormal conditions with reference to the water feed to the boiler arises.

Briefly, the invention comprises means for continuously affecting the flow of water to the boiler; also means for intermittently affecting the control when the need arises, both of these means being automatic; also providing manual means for affecting the flow when any occasion arises; and also means for signalling to the operator any abnormal conditions in reference to the boiler water. A specific purpose of the invention is to provide feed water valves to which these various means can be applied. Other objects of the invention will be apparent from a consideration of the accompanying drawings and the following description thereof.

Of the drawings, Fig. 1 is an elevation of a boiler and its attachments which embody some of the features of my invention; Fig. 2 is a somewhat similar elevation showing additional means; Fig. 3 is an elevation of a specific type of means for operating the feed water valve which is applicable to my invention; Fig. 4 is a plan view of the same, and Fig. 5 is an elevation thereof at 90° from that of Fig. 3; and Fig. 6 is an elevation of a system somewhat similar to that of Fig. 2.

Referring to Fig. 1 which is more or less diagrammatic, the boiler 10 is supplied with water through a feed pipe 11. The flow of water to the boiler is controlled by the feed water valve 12, which is operated in an ordinary manner by the regulator 13, or any suitable type of feed water regulator. As is well understood, when the water rises unduly in the tube 13 the tube contracts and the lever arm 14 is raised, and this in turn raises the arms 15 and 16 and thus closes more the valve 12.

The arm 15 is pivoted to an arm 17, at the point 18, so that any variation in the elevation of the arm 17 will vary accordingly the opening 55 of the valve 12. In order that the level of the

water in the boiler can be controlled independently of the regulator 13, whenever any occasion arises, I provide means in this case for varying the elevation of the arm 17. This means comprise the rotatable shaft 19 upon which the arm 17 is threaded. This shaft is arranged to be rotated by means of an electric motor 22. On the shaft of the motor is mounted the screw 20 which meshes with the wheel 21. The wheel 21 is fixed to the shaft 23 which is coupled coaxially with the shaft 19 by means of the detachable coupling 24.

If it is desired to vary the flow of water to the boiler independently of the boiler regulator 13, the operator, by operating the motor 22 in one direction or the other, may raise or lower the arm 17 by rotating the shaft 19 and thus close or open more the valve 12. This change in the position of the valve may be temporary or permanent as desired. If the water in the boiler surges temporarily the operator can close the feed valve 20 somewhat until the emergency is over; or if he desires to lower the water level elevation permanently he can raise the arm 17 as much as is necessary to reach his purpose.

For convenience of operating the motor, switches may be located at any convenient place, such as the gage board 25, the switch 26 for instance being for the purpose of raising the water in the boiler and the switch 27 for lowering the water. A water level meter 28, mounted on the board, indicates at all times the water level elevation, and lamps 29 and 30, of different colors, may be mounted on the board for indicating any abnormal elevation of the water level.

Also, if desired, a hand wheel 32 may be mounted on the upper end of the shaft 19 by means of which the shaft may be rotated and the water level may be affected as desired. When this wheel 32 is to be operated the coupling 24 is 35 opened, and the arm 17 elevated or lowered by rotating manually the shaft 19.

Fig. 2 illustrates automatic as well as manual means for independently affecting the flow of water to the boiler. In this case the boiler 40 is supplied with water through the valve 41 by means of the ordinary feed water regulator 42. To control the flow independently of this regulator, however, in this case I provide an additional feed water valve 43 in parallel with the valve 45 50 41. This valve 43 may be operated manually by means of the electric motor 44, which is arranged to open or close the valve 43 in any ordinary manner. Mounted at any convenient place, such as on the gage board of the boiler system, are 55

switches 45 and 46. When one of these switches is closed current will flow through one or the other of the solenoids 47 or 48 to operate the switch 49 and thus to operate the motor. For instance, when the switch 45 is closed current passes from the supply line 71 through the connector 73 of the switch 49, and the wire 74 through the switch 45 and thence through the wire 78, wire 77, limit switch 52, solenoid 48 to the supply line 72. The solenoid 48 closes the switch 49 and the motor is operated by means of the connecting wires 83, 84, and 85.

The valve 43 may be partly open ordinarily, if desired, and the water flow merely varied to meet the needs either temporarily or permanently; or this valve may be entirely opened or closed when the flow is so affected. To avoid overload on the circuits, or straining of any of the parts, when the valve is fully closed or opened by the motor, limit or overload switches 51 and 52 may be inserted. The operator in this case may be guided by suitable indicators just as in case of the apparatus of Fig. 1.

In this case I provide also automatic means for operating the valve 43 independently of the regulator 42. This comprises the thermostatic tube 55 which is connected to the boiler by the pipes 56 and 57 substantially the same as is the tube 42. The tube 55 is adapted to operate a lever 58. This lever operates ordinary push button contacts or carries a brush which is adapted to close contacts 33 and 35 or 33 and 34, according as the tube 55 is full of water or steam. If the water rises too high the tube fills, cools, contracts and contacts 33 and 35 are closed. This closes the circuit through the solenoid 47 which causes the switch 49 to be operated to operate the motor to close more or entirely the valve 43.

For instance, when these contacts 33 and 35 are closed the current passes from the supply line 71 through the connector 73, the wires 74, 75, and 76, to the contact 33; thence to the contact 35, wires 36 and 37, solenoid 60, wires 82, 81, and 80, solenoid 47, to the supply line 72, thus operating the switch 49 and the motor 44. If the water sinks too low in the boiler the process is reversed: the solenoid 48 is excited and the motor is operated to open more or entirely the valve 43.

In either case, as soon as the water level elevation changes sufficiently the contacts controlled by the tube 55 will be opened, and the movement of the valve 43 will cease. When the circuit through the contacts 33 and 34 is closed the solenoid 61 will be excited and this in turn will close a switch 63. When the switch 63 is closed the current will flow through the horn 66 and a light 67, signaling to the operator that the water in the boiler is too high. The operator may then check up and see that the automatic operation of the tube 55 is ample, or he may operate the switch 45 thus operating manually the valve 43. Similarly closing the contacts 33 and 35 will excite the solenoid 60, close the switch 62, and blow the horn 64 and light the lamp 65.

It will be understood, however, that the automatic operation of the tube 55 may be limited merely to signaling the condition of the water level by the horns or the lights, leaving to the operator whatever correction may be necessary, just as suggested with reference to the apparatus of Fig. 1.

The system is connected to a generator by the wires 70, 71 and 72. The contact 33 is permanently connected with the wire 71, by means of the wires 74, 75, 76, and 73. The contact 34 is

permanently connected with the wire 72 through the solenoid 48 and the wires 77, 78, 79, and the solenoid 61. The contact 35 is permanently connected with the wire 72 through the solenoid 47 and the wires 80, 81, and 82, and the solenoid 60. The motor is connected with the power lines 70, 71 and 72 through the switch 49 and the wires 83, 84 and 85.

In Figures 3 to 5 I illustrate hydro-electric means for operating the feed water valve which are particularly adaptable to the system of Fig. 1 and which may be applied to the system of Fig. 3. These means comprise a piston 90 working in the cylinder 91 and connected, by means of a shaft 92, with the plunger of the feed water valve 93. Fluid under pressure is passed into the cylinder by means of a pipe 94 and the exhaust is passed out through a pipe 95, by means of an ordinary slide valve 96. The slide valve is operated by the feed water regulator of the system by means of a rod or strut 97 which is operated by the regulator lever in an ordinary manner. The rod 97 operates a lever 98, having its fulcrum 99, Fig. 5, mounted on an arm 100. The arm 100 is threaded on to a shaft 101, which corresponds to the shaft 19 of Fig. 1. The arrangement is about the same as that of Fig. 1: the shaft 101 is operated by the motor 102 through the screw 103, the screw wheel 104, the shaft 105 and the detachable coupling 106.

Pivoted to the lever 98 is a rod 107 which is also pivoted to a lever 108. The lever 108 has its fulcrum 109 fixed with reference to the shaft 92. And also pivoted to the lever 108 is a connecting rod 110 which operates the slide valve 96 to pass fluid under pressure into one end or the other of the cylinder 91. It will be understood that the feed water regulator of this system may be substantially the same as that of Fig. 1, the lever 15 of that figure corresponding to the lever 98 of Fig. 5.

When the water in the boiler rises sufficiently the regulator will raise the free end of the lever 98; this will raise the free end of the lever 108 and thus the slide of the valve 96, passing fluid under pressure into the upper end of the cylinder 91 and thus closing more the feed water valve 93. And the reverse process occurs when the water in the boiler sinks sufficiently to operate the regulator of the system. During these operations the motor 102 is assumed to remain at rest, as this is the normal operation of the feed system.

If, however, it is desired to control the water flow independently of the regulator, this may be done as with the apparatus of Fig. 1 by operating manually the motor. Or the motor can be connected up to automatic means such as are illustrated in Fig. 2. Also, in each of the modifications herein described it is to be understood that the ordinary feed water regulator may be dispensed with, and the feed water valve manually operated with or without the assistance of the automatic signaling thermostat tube 55.

When the main regulator is thus dispensed with the point 36' of its lever, Fig. 1, becomes the fulcrum. For instance if the regulator is rendered inoperative in any manner, so that the lever 15 is at rest, the other operating means would operate the lever 15 around the fulcrum 36'.

Also the system of Fig. 2 could be modified to include one feed water valve only. This arrangement is shown by Fig. 6 in which the feed valve 110 may be similar to the valve 93 and may be

similarly operated by means of the regulator 111 which is connected to the valve system by the strut or rod 97. The motor 102 is operable manually by switches 112 and 113, and it is operable 5 automatically by the thermostatic tube 114.

When the switch 112 is operated to open the contacts 114 and to close the contacts 115, current flows from the supply line 116 through the switch 115, wire 117, solenoid 118, limit switch 10 119, and wires 120 and 121 to the return power line 122. The solenoid 118 closes the motor switch 123, and thus current flows through the motor 102 from the supply line 116, wire 124, switch 123 and wire 125, and then back through 15 wire 126, switch 123 and wire 121 to the line 122. When the switch 113 is operated the motor is rotated in the opposite direction by the solenoid 130.

Similarly, when the switch 131 is operated to close the contacts 132 and also the contacts 133, 20 current flows from the line 116, wire 134, contacts 132, wire 135, switch 112, wire 136, wire 137, solenoid 130, limit switch 138, wires 120 and 121, to the power line 122; thus operating the switch 123 and the motor 102 to open more the valve 110. 25 At the same time, when the contacts 133 are closed by the operation of the switch 131, the current flows from wire 134 through the contacts 133 and wire 140 to the signal lamp 141 and horn 142, and thence through wire 143 to line 122. This 30 signals to the operator that the water is low enabling him to check up and see that the automatic operation is proper. When the switch 145 is operated the motor is rotated in the opposite direction, and the lamp 146 and horn 147 are operated.

It will thus be seen that in case of the system of Fig. 6 the two thermostatic tubes 111 and 114 may operate the feed water valve concurrently but independently of each other. In practice the 40 valve is operated normally by the tube 111, the tube 114 being more for a safety device to prevent flooding or emptying of the boiler, and to signal to the operator when any dangerous condition arises. Also the feed water valve is under the 45 control of the operator by the manual operation of the motor whenever the tube 114 is inoperative. And the valve is operable or adjustable manually by means of the wheel 115 just as in case of the apparatus of Fig. 1.

50 A feature of my invention of importance is the ability to operate the valve controlling mechanism at any distance that may be desired. The gage board may be located in another room or another building and, by running the electric 55 wires from the board to the valve motor the valve can be controlled according to the indications of the level indicator by the switches on the board. Also the high and low thermostat may be located without reference to the location of the feed water valve, as the two are connected only 60 by the electric circuits.

I claim as my invention:

1. In a boiler system, a feed water valve, means 65 responsive to the water level elevation in the boiler for operating the valve, said means comprising a lever, means for varying the position of the

lever fulcrum, an electric motor operatively connected with the later means, and manual means for operating the motor.

2. In a boiler system as claimed in claim 1, in which said manual means is mounted on the gage 5 board of the system.

3. In a boiler system as claimed in claim 1, and additional means for varying the position of the fulcrum while said responsive means is in normal 10 operation.

4. A boiler system as claimed in claim 1, in which varying means comprises a rotatable shaft, an element threaded onto the shaft, the said fulcrum being mounted on the element, and means for operatively connecting the shaft with the motor. 15

5. In a boiler system as claimed in claim 1, in which said varying means comprise a rotatably mounted shaft, an element threaded onto the shaft, the said fulcrum being mounted on the element, means for operatively connecting the shaft with the motor, means for disconnecting the shaft from the motor, and manual means for rotating the shaft independently of the motor. 20

6. In a boiler system, a feed water valve for the 25 boiler, means responsive to the water level elevation in the boiler for operating the valve, manual means for operating the valve when said responsive means are not operating, said manual means comprising an electric switch. 30

7. A boiler system as claimed in claim 6, including a second feed water valve for the boiler mounted in the system parallel with the first mentioned valve, and means responsive to the water level elevation for operating the second 35 valve.

8. In a boiler system, a feed water valve, means for operating the valve, said means comprising a cylinder, a fluid pressure operable piston mounted in the cylinder and operatively connected with 40 the valve, a slide valve for passing fluid under pressure into the cylinder, means responsive to the water level elevation in the boiler for operating the slide valve, and manual means for varying the position of the slide valve independently 45 of the responsive means.

9. A boiler system as claimed in claim 8, and other means responsive to the water level elevation in the boiler for varying the position of the slide valve when the first mentioned responsive 50 means is in operation.

10. In a boiler system, means responsive to the water level elevation in the boiler for affecting the flow of water to the boiler, other means responsive to said level elevation for affecting said 55 flow of water, said latter means comprising means for indicating the said level elevation, and manual means for affecting said flow.

11. In a boiler system, a feed-water valve, means responsive to the water level elevation in the boiler for operating the valve, said means comprising a lever, means for varying the position of the lever fulcrum, said latter means comprising a motor, and manual means for operating the motor. 60

VINCENT V. VEENSCHOTEN. 65
